UNITED STATES PATENT OFFICE.

WERNER LEHMANN, OF LOS ANGELES, CALIFORNIA.

CROCHET-BALL HOLDER.

1,386,121.

Specification of Letters Patent. Patented Aug. 2, 1921.

Application filed July 12, 1920. Serial No. 395,516.

To all whom it may concern:

Be it known that I, WERNER LEHMANN, a citizen of Switzerland, (who has declared his intention of becoming a citizen of the 5 United States,) residing at Los Angeles, in the county of Los Angeles and State of California, have invented a new and useful Crochet-Ball Holder, of which the following is a specification.

10 My invention relates to the art of crocheting being more particularly a holder upon which the crochet ball is supported during the crocheting operation. The principal object of my invention is to produce a device 15 of the character described of simple form and construction which will hold the crochet ball during the unwinding of the ball, the ball being free to rotate during the unwinding operation.

20 Other objects and advantages will appear hereinafter from the following specification and drawings.

Referring to the drawings which are for illustrative purposes only,

25 Figure 1 is a side view of a holder embodying a form of my invention showing the ball mounted thereon.

Fig. 2 is a sectional plan view on line 2—2, Fig. 1.

30 Fig. 3 is a vertical sectional view on line 3—3, Fig. 2, and

Fig. 4 is a perspective view of the frame forming a part of the holder.

A crochet ball, as indicated at 11, is usually formed with a central opening 12 extending therethrough, this opening being formed by a hollow core of cardboard or a similar material indicated at 13, the thread indicated at 14 being wound upon such

40 cardboard to form the ball. The core 13 does not extend entirely through the ball so that during the winding operation a portion of the thread forms slight bulges 15 at the ends of the core.

45 The holder consists of two parts, a supporting member generally indicated at 17 and a frame indicated at 18. The supporting member consists of a flat base 20 upon which is formed a hollow standard 21 which 50 extends upwardly therefrom. The hollow standard 21 is provided with a central bore 22 which extends downwardly from the upper end of such standard, the upper face of the standard being rounded, as indicated at

55 23, for the purposes hereinafter described.

The frame in the form shown consists of

three pieces of wire, the inner ends of which are joined together by solder or in any other suitable manner to form a downwardly extending post 25 which extends into the bore 60 22 of the standard 21. The wires extend outwardly from the post 25 forming rounded arms 26 which engage the upper end of the standard 21 supporting the frame in such manner upon the standard. The wires extend downwardly from that portion of the wires forming the arms to form legs 29, such wires being looped, as indicated at 27, thence extending upwardly, being bent outwardly at their upper ends to form prongs, 70 as indicated at 28.

The holder is used in the following manner:

The legs are pressed inwardly so that the prongs may readily enter the opening in the 75 ball, and, after being inserted therein the pressure of the hand is relieved and the legs spring outwardly so as to engage the lower edge of the inside of the ball as shown in Fig. 3. The engagement of the 80 lower end of the legs with the inside of the ball, as shown in Fig. 3, causes the upper and free ends of the wire to spring outwardly so that the prongs or outer ends of the wire engage the inside of the ball or 85 core 13.

When the ball is placed upon the holder as just described the frame is mounted upon the supporting member by inserting the post 25 into the bore 22 of the standard 21, the 90 post being of smaller diameter than the bore in the standard, the supporting of the ball upon the standard being performed by the curved arms which extend over the upper rounded end of the standard.

95 It will be understood that when so mounted the thread may be pulled from the ball as needed and that the ball and frame will rotate upon the standard to accommodate the pull on the thread. The frictional engagement of the arms with the top of the standard is such that the ball freely moves when the thread is pulled but does not run free enough to permit the thread to be unwound faster than used thereby permitting 100 105 tangles being formed in the thread.

I claim as my invention:

1. A crochet ball holder comprising a supporting member consisting of a base and a standard on the base having a central bore 110 extending into the top of the standard; and a frame arranged to extend into and sup-

port said ball rotatably mounted on the base, said frame consisting of a series of wires having their inner ends united to form a post extending into the bore in the standard, each 5 of said wires extending outwardly from said post forming curved arms rotatably engaging the upper end of said standard, said wires being bent downwardly and upwardly from said arms forming legs having loops 10 at their lower ends arranged to engage said ball, said wires terminating at their upper ends in outwardly extending prongs arranged to engage the interior of said ball.

2. A crochet ball holder comprising a supporting member consisting of a base and a standard on the base having a central bore extending into the top of the standard; and a frame arranged to extend into and support said ball rotatably mounted on the base, said 20 frame consisting of a series of wires having their inner ends united to form a post extending into the bore in the standard, each of said wires extending outwardly from said post forming curved arms rotatably engaging the upper end of said standard, said wires being bent to form legs engaging the inner portion of said ball at the bottom and at the top of said ball.

3. A crochet ball holder comprising a supporting member consisting of a base and a standard on the base having a central bore extending into the top of the standard; and a frame arranged to extend into and support said ball rotatably mounted on the base, said 35 frame consisting of a series of wires having their inner ends united to form a post extending into the bore in the standard, each of said wires extending over the upper end of said post to form a support for the frame and having extended portions arranged to engage the inside of the ball at the bottom and intermediate its ends.

4. A crochet ball holder comprising a stationary standard having a central bore, and

a frame rotatably mounted on said standard, 45 said frame consisting of a post extending into the bore in the standard, wires extending outwardly from said post rotatably resting upon the top of the standard, legs formed of said wires arranged to engage the lower 50 edge of the inside of said ball, and prongs formed on the upper ends of said wires arranged to engage the inside of said ball.

5. A crochet ball holder comprising a stationary standard having a central bore, and 55 a frame rotatably mounted on said standard, said frame consisting of a post extending into the bore in the standard and wires extending outwardly from said post rotatably engaging the top of the standard and downwardly, forming elastic legs engaging the lower edge of the inside of said ball, the upper ends of said wires extending outwardly to engage the upper portion of the inside of said ball.

6. A crochet ball holder comprising a stationary standard having a central bore, and a frame rotatably mounted on said standard, said frame consisting of a post extending into the bore in the standard and spring 70 members secured to said post arranged to rotatably engage the upper end of the standard and having outwardly extending ends arranged to engage the inside of the ball.

7. A crochet ball holder comprising a stationary standard having a central bore, and a frame rotatably mounted on said standard, said frame consisting of a post extending into the bore in the standard and elastic 75 members secured to said post arranged to rotatably engage the upper end of the standard to carry the weight of the ball thereon and having legs arranged to engage the inside of said ball.

In testimony whereof, I have hereunto set 85 my hand at Los Angeles, California, this 6th day of July, 1920.

WERNER LEHMANN.
